Open Middleton Donaldson, Jr.

ATTORNEY.

UNITED STATES PATENT OFFICE.

FREDERICK W. BURCH, OF PUEBLO, COLORADO.

RATCHET MECHANISM FOR CAMP-BEDS.

1,366,241.

Specification of Letters Patent. Patented Jan. 18, 1921.

Application filed October 3, 1919. Serial No. 328,224.

To all whom it may concern:

Be it known that I, FREDERICK W. BURCH, a citizen of the United States, and resident of Pueblo, Colorado, have invented certain new and useful Improvements in Ratchet Mechanism for Camp-Beds, of which the following is a specification.

My present invention relates to improvements in winding and clutch mechanism designed more especially for camping and automobile touring purposes.

The invention aids to provide simple efficient and easily operable means by which the tension on the bed bottom may be adjusted to suit the weight to be carried, and may be easily relieved when the bed is to be knocked down.

With these and other objects in view the invention includes the novel features of construction and arrangement and combination of parts hereinafter described and defined in the appended claims, an embodiment of my invention being illustrated in the accompanying drawings in which:

Figure 1 is a plan view of my improved device partially broken away.

Fig. 2 is a horizontal section.

Figs. 3 to 7 inclusive are detail views.

It will be understood that my invention is designed to be used in connection with a bed bottom which may be wholly of fabric such as canvas or partly of material of the flexible spring bed bottom or wire type which is designed to be supported by a knock down frame and have tension applied when in use.

The frame comprises an end bar 2 preferably of tubular form, to the end of which is pinned a T coupling member 2^a. The opening or passage in the head of this T coupling is designed to receive the end of the side member or bar (not shown) and, to assure the assembling of the parts in proper position, the sockets of the coupling members are preferably made non circular as for example by providing a flat side *a*, the corresponding portions of the ends of the side bars being provided with a correspondingly flattened portion. The side bars are preferably constructed of iron or steel tubing, and the angular ends of castings having portions shaped to be inserted into the tube ends to be pinned therein.

Associated with the bar 2 are the means for applying the proper tension to the bed

bottom which, in the preferred embodiment shown in the accompanying drawings, comprises a tubular member 7 which encircles the member 2 and is designed to be rotatable about said member 2, said member being held concentric with the end bar by collar 2^b.

The end of the bed bottom to which tension is to be applied is detachably secured to this tube by any suitable means.

By the tube 7 upon the member 2 the end of the bed bottom will be wound up on the tube 7, and any desired tension may thus be placed on the bed bottom.

My preferred means for operating the winding roller and for locking and releasing it will now be described.

The end of the rod or bar 2 is provided with a cylindrical socket member 8 which is preferably formed as an integral part of the coupling member 2^a. This socket member provides an annular clutch ring receiving recess around the bar 2 within which is located a clutch ring 9 which has locking projections 9^a designed to engage corresponding recesses 8^a in the annular wall of the member 8.

A spring 10 located between the side wall of the socket and the clutch ring tends to force the latter outwardly to normally hold the clutch teeth in engagement as herein-after described.

Pinned or otherwise suitably secured on the end of the winding tube 7 is a collar 11 which has ratchet teeth 11^a formed on the end thereof designed to coact with corresponding ratchet teeth 9^b on the ring 9. As the ratchet ring is held against rotation by the projections 9^a engaging the recesses 8^a the roller may be rotated to place tension on the bed bottom, the engagement of the ratchet teeth 11^a and 9^b holding it in any position to which it may be adjusted.

For conveniently rotating the winding roller I place around the collar 11 a rotatable ring 12 which has an internal pawl 12^a designed to engage an annular series of ratchet teeth 11^b on the collar 11, these teeth being preferably formed on an annular or peripheral flange on the collar and the ring 12 being rotatably held in position by flanges or side plates 13 overlapping said flange. A handle 14 preferably hinged or folding, is secured to the ring 12 by which

the latter may be oscillated, and, through the pawl and ratchet mechanism described, the roller may be rotated.

For disengaging the pawl and ratchet mechanism 11^a—9^b, above described to release the roller, I provide a rotatable collar 15 encircling the socket member 8 which has a spring pressed dog 15^a designed to engage either notch of a pair of notches or 10 recesses 8^x in the periphery of member 8.

This collar 15 has a flange overlying the face of the member 8 from which project a pair of cams or beveled projections 15^b designed to coact with correspondingly bevelled faces on the locking projections 9^a.

When the collar 15 is oscillated in one direction so that the locking dog registers with one of the recesses the cams 15^b will engage the projections 9^a and force the 20 ratchet ring 9 inward into the socket member until the ratchet teeth 9^b are out of engagement with the teeth 11^a on the roller. When the collar is rotated so as to cause the locking dog to engage the next notch the 25 cams or inclines are shifted so as to allow the ratchet ring to be shifted until its teeth engage the ring on the winding roller, enabling the roller to be rotated and held in tension maintaining position, the spring, 30 however, yielding to enable the ratchet teeth to slip by each other.

Instead of providing a reciprocating locking dog or pawl 12^a, I may provide a pivoted dog 12^x having a rounded boss α at its end designed to rest in a recess α' in the ring 12 so that the pawl may be slipped in before the side plates 12 are secured in place and thus held without other fastening means.

Having thus described my invention what 40 I claim is:

1. In combination, a bar or rod, a winding cylinder rotatably carried by the said bar, a pawl and ratchet mechanism, an oscillating handle connected with said cylinder by pawl and ratchet mechanism, ratchet clutch mechanism interposed between said bar and cylinder, and means for disconnecting said ratchet clutch mechanism.

2. In combination, an end bar or rod, a cylindrical roller rotatable about said bar, inclined clutch teeth on the end of said roller, a clutch ring slidably and non rotatably held in relation to the bar carrying said roller and having teeth coacting with the teeth on the roller, a spring pressing said ring toward the roller, a rotatable cam ring designed to move said ring against the tension of the spring to disengage the teeth, and means for rotating said roller.

3. In combination, an end bar or rod, a cylindrical roller rotatable about said bar, inclined clutch teeth on the end of said roller, a clutch ring slidably and non rotatably held in relation to the bar carrying said roller and having teeth coacting with the teeth on the roller, a spring pressing said ring toward the roller, a rotatable cam ring designed to move said ring against the tension of the spring to disengage the teeth, a ring member encircling one end of the roller, pawl and ratchet means connecting said ring member and roller, and a folding handle connected to said ring member.

In testimony whereof, I affix my signature.

FREDERICK W. BURCH.
